INTEGRAL CONTAINER FOR A MAGNETIC MEMORY DISC PACK

Charles W. David, Marina del Rey, and Raymond Stuart-Williams, Pacific Palisades, Calif., assignors, by mesne
assignments, to MRX Corporation, Hawthorne, Calif.,
a corporation of California

Filed May 23, 1966, Ser. No. 2,403

Term of patent 14 years

(Cl. D58—11)

We claim:

The ornamental design for an integral container for a magnetic memory disc pack, substantially as shown.
